(57) **CLAIM**

The ornamental design for an exit sign with U-shaped lower
lighting, as shown and described.

DESCRIPTION

FIG. 1 is a front perspective view of an exit sign constructed
in accordance with our new design, with the exit sign shown
positioned along a wall;

FIG. 2 is a front view of the exit sign of FIG. 1;

FIG. 3 is a rear view of the exit sign;

FIG. 4 is a left side view of the exit sign;

FIG. 5 is a right side view of the exit sign;

FIG. 6 is a top view of the lighted exit sign; and,

FIG. 7 is a bottom view of the lighted exit sign.

The broken lines in FIG. 1 depict a wall to which the lighted
exit sign of FIGS. 1–7 can be attached, and the additional the
broken lines in FIGS. 1, 2 and 5 depict a test button and AC
indicator arrangement. This broken line structure is for
illustrative purposes only and forms no part of the claimed
design.
